Fig. 1. 2

Fig. 2.

A black and white line drawing of a dog's head and front paws. The dog is facing forward, with its head tilted slightly upwards. Its ears are large and floppy, and its eyes are wide and expressive. The dog's front paws are extended downwards, with its claws visible. Several measurements are indicated in inches: the width of the head is labeled as 25, the height of the head is labeled as 24, the length of the front leg is labeled as 15, the length of the front paw is labeled as 14, and the length of the front toe is labeled as 23. The drawing is done in a simple, sketchy style with some dashed lines for reference.

ADVERTISING DEVICE

Richard F. Outcault, Flossmoor, Ill.

Application January 19, 1933, Serial No. 652,440

6 Claims. (Cl. 40—138)

This invention relates to advertising devices, being especially designed and constructed for use in public passenger vehicles such as railroad trains, and adapted to be operated by the motion inherent in such vehicles.

An object, for example, is to provide an advertising sign in such a vehicle which may be wholly or partially movable, said movement being derived from the motion of the vehicle. It is well established that a moving advertisement is one of the most effective of advertisements, and the aim has been and the result accomplished is to provide a sign of the above nature which is capable of creating an unusual vital or dramatized effect, and especially adapted to arrest the interest of observers. The invention not only has for its object the provision of such an advertising device and operative means therefor, but has also, among other objects, the provision of means which will be simple in operation, easy to manufacture, and relatively inexpensive. These and others of the objects and advantages of my invention will appear in the specification hereinafter set forth.

The invention will be best understood by reference to the accompanying drawings of some concrete exemplifications which have been selected to illustrate my invention, and in which: Fig. 1 is an elevational view, partly in section, of a preferred form of my invention;

Fig. 2 is a sectional view, taken on the line 2—2 of Fig. 1;

Fig. 3 is an elevational view of another form of my invention, with operating mechanism shown in dotted lines;

Fig. 4 is a sectional view, taken on the line 4—4 of Fig. 3;

Fig. 5 is an elevational view, partly in section, illustrating another form of operating mechanism;

Fig. 6 is a sectional view, taken on the line 6—6 of Fig. 5;

Fig. 7 is an elevational view, partly in section, illustrating another form of my invention; and

Fig. 8 is a sectional view, taken on the line 8—8 of Fig. 7.

The form of construction illustrated in the drawings in Figs. 1 and 2 includes a front wall 10 and a rear wall 11. The front wall is less than one-half as high as the rear wall, and the two are separated by a space 12 therebetween, the front wall being fixed to the rear wall in an obvious manner. The two walls are adjusted so that when viewed from the front after advertising matter has been placed upon the walls the

two walls may be regarded as presenting one integral advertising design. For example, the form shown in Fig. 1 viewed from a distance affords the illusion of a single wall having thereon the face of a man, printed matter, and articles illustrating the subject of the printed matter, such as bottles of shaving lotion.

Between the front wall and the rear wall are side boards 13 and 14, top board 15, and base board 16 by which the space 12 is formed. Attached to the side board 14, in any suitable manner, is a spring 17 having a sliding weight 18. This spring extends laterally from the side board 14, and pivoted to the end of it is a device in the form of an integral wrist and hand 19. The member 19 is provided with a slot 20, and extending therethrough is a pin 21 fixed in the front and rear walls.

The device illustrated in Figs. 1 and 2 is adapted to be affixed to the upper wall portion of, for example, the interior of a railroad car, and when viewed in combination with the movable element 19 presents the effect of a man's hand being rubbed over one side of his face, inferentially applying shaving lotion. This result is accomplished, as will be manifest, by means of the vertical movement of the train which is imparted to the spring and which causes the hand to move vertically upwardly and downwardly in correspondence with the motion inherent in the car. The slot 20 and pin help to guide the operation of the hand, and the sliding weight 18 is provided for adjustment.

The form shown in Fig. 3 comprises a front wall 10 and a rear wall 11, combined as in the form shown in Fig. 4. The front wall 10 is provided with a design of the body of a dog without a head. A rod 22 having a weight 23 and forming a pendulum is pivotally affixed, as at 24, to the top board 15. The bar 22 extends upwardly and outwardly from the top board 15, and affixed to its outer end is a member 25 having thereon a design of a dog's head.

The operation of this form of the invention will also be manifest without much explanation. When the device is attached to the side wall of a car, longitudinal movement of the car will be utilized to swing the pendulum and therefore swing the connected head of the dog to and fro, and the effect will be an animated design advertising, for example, dog biscuits. If the device were applied to the front wall or the rear wall of the car the lateral movement of the train would operate to manipulate the pendulum.

In Fig. 5 there is illustrated a form of operat-

ing means for translating the movement of the car into, for example, pivotal movement. In this form there is affixed to the side board 14 a laterally extending spring 26 having a weight 27 slidably connected thereto in any suitable manner. Pivoted connected to the spring, as at 28, is a link 29, which is in turn pivotally connected at 30 to one arm of a bell crank 31. The bell crank 31 is pivoted at 32, and the other arm 10 of the bell crank is in turn pivotally connected at 33 in an obvious manner to a moving part 34 of the entire advertising device. In the form shown this part has thereon the words "Motor Airplanes." It will be noted that the spring 26 15 under the transmission of vertical motion from the train will cause the bell crank 31 to swing to and fro on its pivot 32 and correspondingly impart to-and-fro motion to the part 34.

Referring to the form shown in Fig. 7, this 20 form comprises a front board 35, rear board 36, top board 37, and bottom board 38. Fixed in any suitable manner to the top board 37, to the under surface thereof, is a housing 39. Located in the housing is a trackway 40 upon which is adapted to reciprocate a ball 41. The ball 41 has a shaft 42 provided with hubs 43. The shaft 42 extends through a slot 44 in the housing 39. Mounted upon the shaft 42 is an 25 arm 45 having a weight 46 combined therewith to form a pendulum. The upper end of the arm 45 extends upwardly from the top board 37 through a slot 47 and outwardly from the front board 35, and has affixed thereto at its extremity a movable element in the form of a zeppelin.

30 By means of this arrangement, longitudinal movement of the car may be transmitted so as to cause reciprocation of the ball 41 and corresponding reciprocatory movement backward and forward of the zeppelin above the sign when the 35 same is affixed to the side wall of the car. By 40 the same arrangement, because the ball 41 is loosely mounted upon the shaft 42, the pendulum is adapted to be swung as a result of the longitudinal movement of the car to correspondingly impart a swinging or curvilinear movement to the zeppelin, in addition to the other 45 resultant movement. If the device shown in Fig. 7 is applied to the front wall of the car the result will be substantially the same, though perhaps different in degree.

50 The embodiments heretofore selected to illustrate the principle of my invention have each involved a stationary and a movable element. However, it is not indispensable to the practice 55 of the invention to have a stationary element per se. A coil spring, for example, might be attached to the upper portion of the interior wall of a car, at one end, and an advertising device might be applied to the other end of this 60 spring. If the wall to which this spring were applied were a side wall, lateral, vertical and longitudinal motion would be transmitted to the spring and to the advertising device. This would also be true if the device were applied to the 65 front wall. In addition, a weight might be provided upon the coil springs, slidably mounted for adjustment.

In the preferred form shown a frame has been provided which will function to hide the operating mechanism.

I have illustrated and described a number of concrete exemplifications which I have selected 5 to illustrate the principle of my invention. My invention of course is not limited to these exemplifications, but these may be changed in numberless respects without departing from the spirit of the invention. I, therefore, do not wish 10 to be limited to the precise details of construction set forth, but desire to avail myself of all of such variations and modifications as come within the scope of the appended claims.

Having thus described my invention, what I 15 claim as new and desire to secure by Letters Patent is:

1. An advertising device of the character described, including a wall, a laterally extending spring located on one side of said wall and 20 adapted to transmit motion, an element connected to said spring and adapted to be moved by said spring, and a pin adapted to be extended through a longitudinal slot in said element, the 25 diameter of the pin being only slightly less than the width of the slot whereby to guide the movement of said element.

2. An advertising device of the character described, including a wall, a spring located on one 30 side of said wall and adapted to transmit motion, an element connected to said spring and adapted to be moved by said spring, and a pin adapted to be extended through a longitudinal slot in said element.

3. An advertising device of the character described, including a wall, a laterally extending spring located on one side of said wall and 35 adapted to transmit motion, an element connected to said spring and adapted to be moved by said spring, a weight slidably connected to 40 said spring, and a pin adapted to extend through a longitudinal slot in said element.

4. An advertising device of the character described, including a wall, a spring located on one 45 side of said wall and adapted to transmit motion, an element connected to said spring and adapted to be moved by said spring, a weight slidably connected to said spring, and a pin adapted to extend through a longitudinal slot in said element.

5. An advertising device of the character described, including a wall, a laterally extending spring located on one side of said wall and 55 adapted to transmit motion, an element connected to said spring and adapted to be moved by said spring, and a pin adapted to be extended through a longitudinal slot in said element.

6. An advertising device of the character described including a wall, a laterally extending spring located on one side of said wall and 60 adapted to transmit motion, an element connected to said spring and adapted to be moved by said spring, and means adapted to extend through a longitudinal slot in said element whereby to guide 65 the movement of said element.

RICHARD F. OUTCAULT.
